EXCHANGEABLE HEEL

Pawel Niedworok, Katowice, Silesia, Poland

Application November 4, 1938, Serial No. 238,903
In Poland November 9, 1937

1 Claim. (Cl. 36—36)

The present invention is directed to an exchangeable heel of a shoe, which can be easily exchanged by the person wearing the shoe and does not change the height of the regular heel.

For this purpose I provide the regular heel with a cutting for an exchangeable plate, having holes for plugs fixed to the heel. The plate is put upon the plugs, so that it comes into contact with the back-wall of the cutting. The height of the plate corresponds to the height of the cutting, so that the upper surface of the plate is on a level with the upper surface of the heel. I can use a plate of aluminium, leather, synthetic resin, gum or the like.

I have found that it is not necessary to provide holes and plugs if the upper surface of the cutting and the corresponding lower surface of the plate are provided with layers of an adhesive substance. After drying of the named layers the plate can be pushed into the cutting and pressed against the heel. In such a way I obtain a binding, which avoids an unintentional loosening of the plate.

If the front rim of the plate is worn, the same can be taken off and turned so that the rim not worn and touching the back-wall of the cutting is used as the front rim.

In the accompanying drawing I have shown one form of the new heel.

In the drawing:

Fig. 1 is a perspective view of the plate.

Fig. 2 is a perspective view of the shoe heel showing the recess for receiving the plate.

The regular heel *a* is provided with a cutting or recess *b*, limited partially by a wall *c*. In this cutting I push the plate *d*, having holes *f* for plugs *e* of the heel *a*. After wearing of the rear rim of the plate may be turned so that the rim touching the wall *c* is arranged adjacent the rim *h* of the heel. The shoulders or projections *k* extend into cuttings or grooves *i* and avoid the displacing of the plate *d*.

I claim :

In a shoe heel having a circular shaped rear edge and a recess extending forwardly from the rear edge terminating in a circular shaped wall corresponding to the curvature of the rear edge of the heel, a pair of projections arranged diametrically opposite each other at the rear ends of said wall, two pins carried by the heel projecting from the surface thereof and circumferentially spaced with respect to said projections and arranged diametrically opposite each other, a substantially circular shaped plate having two holes extending therethrough for receiving said pins and lateral grooves extending along the thickness of the plate for receiving said projections whereby the plate may be mounted in two positions in the recess and two inverted positions in the recess.
